DESIGN FOR A FLOOR COVERING OR THE LIKE

Harold R. Sauer, Hazardville, Conn., assignor to Bigelow-Sanford Carpet Co., Inc., Thompsonville, Conn., a corporation of Massachusetts

Application June 28, 1940, Serial No. 93,315

Term of patent 7 years

To all whom it may concern:

Be it known that I, Harold R. Sauer, a citizen of the United States, residing at Hazardville, in the county of Hartford and State of Connecticut,
have invented a new, original, and ornamental Design for a Floor Covering or the like, of which the following is a specification, reference being had to the accompanying drawing, forming a part thereof.

The drawing is a plan view of a floor covering
or the like showing my design.

I claim:

The ornamental design for a floor covering or the like, substantially as shown.

HAROLD R. SAUER.
